UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A BOTTLE.

Application filed June 17, 1921. Serial No. 478,449. Term of patent 3½ years.

To all whom it may concern:

Be it known that I, ANDREW J. SANFORD, a citizen of the United States of America, residing at Newark, in the county of Licking and State of Ohio, have invented a new, original, and ornamental Design for a Bottle, of which the following is a specification, reference being had to the accompanying drawing, forming part thereof.

The figure is a side elevation of my design.

In the drawing the lower portion of the bottle is provided with a plurality of flutes extending part way from the base, which may be termed half flutes. Above the flutes appears a plane band and above this plane band is arranged a second series of flutes alined symmetrically with the lower flutes.

I claim:—

The ornamental design for a bottle as shown and described.

ANDREW J. SANFORD.
